CLAIM

The ornamental design for frame for glasses as shown and described.

DESCRIPTION

FIG. 1 is a front view of the frame for glasses in a closed position;

FIG. 2 is a front view of the frame for glasses in a linearly displaced open position; and,

FIG. 3 is a front view of the frame for glasses in an angularly displaced open position.

The broken lines shown in the drawings depict portions of the frame for glasses or frame for spectacles and form no part of the claimed design. The additional broken lines shown in a circle format are for the purposes of disclosing the boundaries of the claim and form no part of the claimed design.
